United States Patent Office

Des. 206,566
Patented Dec. 27, 1966

206,566

BICYCLE

Jack Fried, 555 S. Broadway, Los Angeles, Calif. 90013

Filed Dec. 7, 1965, Ser. No. 124

Term of patent 7 years

(Cl. D90—8)

Fig. 1

The dominant features of my design reside in the portions shown in full lines.

I claim:

The ornamental design for a bicycle, as shown and described.
